US00D801967S

(12) **United States Design Patent** (10) Patent No.: **US D801,967 S**
(45) Date of Patent: ** Nov. 7, 2017

(54) **WIRELESS DRIVE**

- (71) Applicant: **Seagate Technology LLC**, Cupertino, CA (US)
- (72) Inventors: **Ash Razdan**, San Jose, CA (US); **Jeffery Griffiths**, Dublin, CA (US); **Ming-Hsueh Tsai**, Taipei (TW)
- (73) Assignee: **SEAGATE TECHNOLOGY LLC**, Cupertino, CA (US)

(**) Term: **15 Years**

(21) Appl. No.: **29/536,699**

(22) Filed: **Aug. 19, 2015**

Related U.S. Application Data

- (63) Continuation of application No. 29/452,661, filed on Apr. 19, 2013, now Pat. No. Des. 739,405.

(57) **CLAIM**

The ornamental design for a wireless drive, as shown and described.

DESCRIPTION

FIG. 1 is a front perspective view of an wireless drive showing our new design;

FIG. 2 is a top view and thereof;

FIG. 3 is a bottom view thereof;

FIG. 4 is a left side view thereof;

FIG. 5 is a right side view thereof;

FIG. 6 is a front side view thereof; and,

FIG. 7 is a rear side view thereof.

The broken lines are included for the purposes of illustrating portions of the wireless drive and form no part of the claimed invention.

1 Claim, 5 Drawing Sheets
